SELF-ADJUSTING TAPPET

George H. Hufferd, Shaker Heights, Ohio, assignor to The Weatherhead Company, Cleveland, Ohio, a corporation of Ohio

Application April 19, 1945, Serial No. 589,234

2 Claims. (Cl. 123—90)

1

My invention relates to tappets and concerns particularly valve tappets for gas engines.

One of the objects of my invention is to provide self-adjusting valve tappet.

The principal object of the invention is to compensate for variations in length of valve stems, valve rods or other operating rods for communicating reciprocating motion.

It is an object of the invention to overcome lost motion in internal combustion engines and to avoid variation of period and timing of valve opening as well as to avoid noise and wear of loose parts.

Another object is to compensate for the effect of variations in temperature on length of the valve rod and to avoid undue loss of efficiency of an internal combustion engine where the engine is still cool.

More specifically, an object is to provide for close adjustment of tappets while the engine is cool as well as when heating up.

A further object is to provide self-elongation and contraction of a tappet without external connections or controls.

Still another object is to provide reliable self-contained hydraulic compensation for tappets in which paths for uncontrolled leakage of hydraulic fluid are eliminated.

A further object is to provide hydraulic compensation for a tappet in which passage of hydraulic fluid from one part to another of the tappet is limited to predetermined means for metering the flow.

Other and further objects, features and advantages of the invention will become apparent as the description proceeds.

In carrying out my invention in accordance with a preferred form thereof, I provide a valve tappet comprising two relatively movable parts in the form of a cylinder and a piston, the cylinder being filled with a hydraulic fluid, such as oil, and the piston having a reservoir therein. A metering orifice and a check valve are provided between the reservoir and the cylinder. The arrangement is such as to tend to cause fluid to be transferred from the piston reservoir to the cylinder through the check valve for the purpose of lengthening the tappet and to return through the metering orifice for the purpose of contracting the tappet when necessary.

A better understanding of the invention will be afforded by the following detailed description considered in conjunction with the accompanying drawing and the scope of the invention will be set forth in the claims.

2

In the drawings:

Fig. 1 is a longitudinal sectional view of a poppet valve and stem with a self-adjusting tappet therefor forming an embodiment of my invention;

Fig. 2 is a longitudinal sectional view of a modification in the tappet illustrated in Fig. 1; and

Fig. 3 is a cross-sectional view of the apparatus of Fig. 2 represented as cut by a plane 3—3 indicated in Fig. 2.

Like reference characters are utilized throughout the drawings to designate like parts.

Referring to Fig. 1 the arrangement shown therein by way of illustration comprises a portion of a casing 11 for an internal combustion engine such as a gasoline engine for example, having a conventional poppet valve 12 controlled by a valve stem 13 or controlled by a valve rod represented by the rod 13 slidable in a suitable guide or bushing 14. A valve spring 15 is provided for normally closing the valve 12 by moving the stem 13 in the downward direction. A tappet 16 is provided for transferring the action of a valve operating cam 17 to the valve rod 13. As in conventional constructions the tappet 16 has a hardened portion 18 adapted to ride on the cam 17 and a hardened surface 19 adapted to contact the lower end 21 of the rod 13.

The tappet 16 comprises two parts 22 and 23 which are relatively movable longitudinally, although, as will be explained hereinafter, the extent of movement required is relatively limited. One of these parts, for example, the part 22, takes the form of a hydraulic cylinder and the other which is the part 23 takes the form of a piston. A suitable relatively incompressible hydraulic fluid 24 such as oil, for example, is provided for filling the cylinder 22, and a reservoir 25 is formed in the piston 23 for supplying oil to the cylinder 22 to extend the tappet length.

The piston 23 and the cylinder 22 are each closed at the outer end and the piston 23 is provided with an inner transverse wall 26.

There are means permitting restricted passage of the hydraulic fluid or oil between the reservoir 25 and the cylinder 22. A minute passage 27 is formed in the transverse wall 26 for permitting metered or accurately controlled transfer of oil to the reservoir 25 from the cylinder 22. For quick return of oil to the cylinder without leakage back into the reservoir 25, a suitable check valve 28 is provided which is shown for the sake of illustration as being of the spring-pressed ball type.

The piston 23 is arranged to be slidable within the cylinder 22 at the open or upper end thereof. In the specific arrangement illustrated, the piston 23 is provided with an expanded or flaring lower end 29 serving as a guide slidably fitting within the cylinder 22. In the arrangement of Fig. 1 suitable means are provided for resiliently expelling or tending to expell hydraulic fluid from the reservoir 25 into the cylinder 22. Such means may take the form of a closed air or gas filled ball or inflated bulb 31 composed of rubber or synthetic plastic or other suitable flexible impervious material.

A seal is provided between the cylinder 22 and the piston 23 and the arrangement is such that no hydraulic fluid can leak back from the cylinder 22 to the reservoir 25 without passing through the metering orifice 27. In this manner exact control of the fluid passage is obtained. In the specific arrangement illustrated in Fig. 1 the parts 22 and 23 are sealed to each other by means of a gasket or ring of flexible material, such as rubber or the like 32. The piston 23 is formed with a reduced-diameter upper portion or neck 33 to provide space for the sealing ring 32 between the neck 33 and the inner surface of the upper end of the cylinder 22. Preferably surfaces of the sealing ring 32 are cemented to the surfaces of the piston neck 33 and the cylinder 22 and then bonded by vulcanization.

When the engine starts up cold with any looseness of the tappet 16 between the cam 17 and the valve rod 13, the pressure bulb 31 expells oil from the reservoir 25 through the check valve 28 into the cylinder 22 in order to extend the tappet and pick up the looseness. The design is such that the pressure on the fluid produced by the bulb 31 is insufficient to counteract the strength of the spring 15, so that no compression of the spring 15 is produced by the tendency of the hydraulic fluid or oil to pass from the reservoir 25 to the cylinder 22.

When the cam 17 rises the body of oil 24 is subjected to pressure by a force of the cam against the surface 18 and the tappet 32 is driven upward against the lower end 21 of the valve rod 13 so as to open the poppet valve 12. A minute amount of oil is pushed under pressure from the cylinder 22 back through the orifice 27 into the reservoir 25. However, the orifice is of sufficiently small diameter so that the small leakage of oil taking place will not prevent requisite opening of the poppet valve 12. The oil returned to the reservoir 25, however, tends to produce momentarily a slight shortening of the tappet and consequently would tend to introduce a slight clearance. Nevertheless, owing to the fact that the dwell of the cam 17 is longer in the downward position of the follower 18 than during the 90 degrees of cam rotation during which the follower 18 is caused to rise, oil is permitted to travel back through the orifice 27 and the check valve 28 to re-extend the tappet before the next upward stroke. Consequently, no clearance occurs between the tappet end 19 and the lower end of the push rod 21, during the power stroke of the cam 17. Thus the tappet constantly hunts for its correct length without ever being out of limits of clearance.

It will be observed that the orifice 27 is somewhat off-center so that there is a tendency for the oil in passing back and forth between the reservoir 25 and the cylinder 22 to introduce turbulence in a body of oil 24, thereby tending to

cause some flow of oil along the surfaces of the cylinder 22 to cool the cylinder.

Since the oil 24 cannot return to the reservoir 25 on the upward stroke of the stem 17 except through the orifice 27, the return flow of oil is precisely metered and constancy and regularity of operation of the poppet valve 12 in response to the operation of the cam 17 is obtained.

Preferably the arrangement is such that the hydraulic fluid 24 cannot leak around the lower edges of the open end of the piston 23 back into the reservoir 25 in order that the only flow of hydraulic fluid from the cylinder 22 to the reservoir 25 would be the metered flow through the orifice 27. This is accomplished in the arrangement of Fig. 1. However, my invention is not limited to the specific arrangement illustrated in Fig. 1. For example, as illustrated in Fig. 2 a piston 23' substantially uniform in diameter fits against the internal surface of the cylinder 22. The upper end of the piston 23' extends beyond the open upper end of the cylinder 22. In this case, however, the sealing between the cylinder 22 and the piston 23' is accomplished by means of an O-ring 34 which comprises a suitable resilient material such as rubber or synthetic compound fitted loosely in an annular channel 35 of greater normal cross-section than the O-ring 34, but of less depth than the uncom-pressed diameter of the ring 34.

A metering orifice 27' is provided in the inner transverse wall 26 of the piston 23' the orifice 27' being very close to the outer side wall of the piston 23'. A vent 36 is preferably provided at the upper end of the otherwise closed piston 23' for relieving air pressure above the transverse inner wall 26 and permitting oil 24 to flow freely into the reservoir 25 and to flow freely therefrom through the orifice 27'.

For causing transfer of hydraulic fluid or oil from the reservoir 25 to the cylinder 22, in place of the compression bulb 31, shown in Fig. 1, a spring 37 is provided which is arranged to push the piston 23' upward in the direction of extension of the tappet 16. The spring 37 is shown as a compression spring mounted within the cylinder 22 between the lower inner surface thereof and the lower surface of the transverse piston wall 26.

The operation of the arrangement of Fig. 2 may be similar to that of the arrangement of Fig. 1. Should any clearance occur between the cam 17 and the lower end of the valve rod 21, the spring 37 causes the piston 23' to move away from the lower end of the cylinder 22 and to transfer hydraulic fluid from the reservoir 25 to the cylinder 22. Upon the power stroke of the cam 17 a contraction of the tappet 16' is resisted by the limitation in the quantity of oil or hydraulic fluid capable of flowing through the orifice 27'. Any requisite contraction of the tappet is provided by the slow rate of flow of hydraulic fluid through the orifice 27'.

Owing to the fact that very little relative motion takes place between the cylinder 22 and the piston 23 or 23' very little flexing of the flexible bushing 32 or very little rolling of the O-ring 34 is required.

Although the foregoing description is necessarily of a detailed character, in order that the invention may be completely set forth, it is to be understood that the specific terminology is not intended to be restrictive or confining, and that various rearrangements of parts and modifications of detail may be resorted to without de-

parting from the scope or spirit of the invention as herein claimed.

I claim:

1. A self-adjusting tappet comprising a cylinder member, a piston member telescoped with said cylinder member, said piston and cylinder members having slidably engaging portions cooperating to form a hydraulic pressure chamber, said piston member having a neck of smaller diameter than said cylinder member and disposed outwardly of said slidably engaging portions, a seal of flexible rubber-like material extending between said cylinder and the neck of said piston member and bonded to each member for preventing escape from the tappet of the fluid leaking from said pressure chamber past said piston member, a hydraulic reservoir chamber formed in one of said members, said pressure chamber and reservoir chamber having a common wall portion integral with one of said members, liquid transfer port means formed in said common wall portion for fluid transfer between said chambers, hydraulic fluid within said pressure chamber and partially filling said reservoir chamber, resilient means in one of said chambers for causing transfer of liquid through said transfer opening from the reservoir chamber to the pressure chamber to thereby allow relative movement of said members in order to increase the tappet length, the wall portions of said piston and cylinder members that define said hydraulic pressure chamber being imperforate except for said liquid transfer port means between said pressure and reservoir chambers, said fluid sealing means blocking flow of liquid out of said pressure chamber in normal operation and insuring that all fluid transfer between said chambers occurs through said transfer means, said liquid transfer port means forming the sole fluid passage communicating with said reservoir chamber.

2. A self-adjusting tappet comprising a cylinder member, a piston member telescoped with said cylinder member, said piston and cylinder members cooperating to form a hydraulic pressure chamber, said piston member having a neck of smaller diameter than said cylinder member, a seal of flexible rubber-like material extending between said cylinder and the neck of said piston

member and bonded to each member for preventing escape from the tappet of fluid leaking from said pressure chamber past said piston member, a hydraulic reservoir chamber formed in one of said members, said pressure chamber and reservoir chamber having a common wall portion integral with one of said members, liquid transfer port means formed in said common wall portion for fluid transfer between said chambers, hydraulic fluid within said pressure chamber and partially filling said reservoir chamber, an inflated flexible bulb filling the remainder of said reservoir chamber for causing transfer of liquid through said transfer opening from the reservoir chamber to the pressure chamber to thereby allow relative movement of said members in order to increase the tappet length, the wall portions of said piston and cylinder members that define said hydraulic pressure chamber being imperforate except for said liquid transfer port means between said pressure and reservoir chambers, said fluid sealing means blocking flow of liquid out of said pressure chamber in normal operation and insuring that all fluid transfer between said chambers occurs through said transfer means, said liquid transfer port means forming the sole fluid passage communicating with said reservoir chamber.
